UNITED STATES PATENT OFFICE.

EDWARD CRAIG, OF ST. JOSEPH, MICHIGAN, ASSIGNOR TO SARANAC MACHINE COMPANY, OF BENTON HARBOR, MICHIGAN, A CORPORATION OF MICHIGAN.

WIRES HANDLE.

1,205,331.

Specification of Letters Patent. Patented Nov. 21, 1916.

Application filed April 17, 1915. Serial No. 21,965.

To all whom it may concern:

Be it known that I, EDWARD CRAIG, a citizen of the United States of America, and resident of St. Joseph, Berrien county, Michigan, have invented a certain new and useful Improvement in Wire Handles, of which the following is a specification.

My invention relates to wire handles such as those employed on fruit baskets.

Generally stated, the object of my invention is to provide a wire handle which can be readily attached to baskets of this kind, in which the two upright portions below the grip of the handle will be held against inward displacement by portions of the wire which bear directly against the outer edges of the basket rim, and having horizontally elongated jaws which bear against the basket to hold the handle upright.

It is also an object to provide certain details and features of construction tending to increase the general efficiency and serviceability of a wire basket-handle of this particular character.

In the accompanying drawings—Figure 1 is a perspective of a fruit basket provided with a wire handle embodying the principles of my invention. Fig. 2 is an enlarged elevation of one side portion of said handle. Fig. 3 is an enlarged detail section on line 3—3 in Fig. 1. Fig. 4 is a perspective of one of the attaching end portions of the handle, showing the condition of the same before the sharp prong is bent and inserted outward through the rim of the basket.

As thus illustrated, my invention comprises a length of wire bent to provide a horizontal or handle portion A, outwardly inclined side portions B, provided with shoulders b which rest upon the cover C of the basket D, the latter being of the well known form and shape, such as those used for peaches and grapes and other fruits. Also, the lower portions of said handles are bent to provide attaching devices E, as shown in Figs. 1, 2, 3 and 4, the formation and mode of operation of which devices are as follows: The extreme end portion of the wire is sharpened and bent outward to form a prong 1 which extends through the rim portion d of the basket. From this prong 1 the wire extends upwardly inside of the basket to form a vertical straight portion 2, and is then bent outward and across the upper edge of the basket rim to form

the short section 3, then downward to form the straight vertical section 4, then at right angles and horizontally to form the portion 5, then downward at 6 to form a sharp bend in the wire, then horizontally again to form 60 the bottom section 7, then upward at the sharp bend 8, then horizontally to form a straight section 9, then upward to form a straight vertical section 10, which latter then joins the shoulder b previously described. 65 It will be seen that the two portions 4 and 10 are brought tight together, and that the portions of the wire immediately below form a T-shaped head which bears hard against the outer surface of the basket rim, to serve as a 70 clamping jaw, thereby preventing the handle from swinging over in either direction. In other words, this T-shaped head provides an extended bearing of any desired length for the fastening device on the outer surface of 75 the basket, and thus tends to prevent the handle from tipping over in either direction.

In Fig. 4 the fastening device E, which is the same at both sides of the basket, is shown in condition to be slipped downward over 80 the side of the basket, and to then have the prong 1 inserted through the basket rim by bending the wire portion 2 against the inner surface of the basket, as shown in Fig. 3. The point of the prong 1, when the handle 85 is thus supplied, is just below the portion 7, or may be short enough so that it does not quite extend through the basket rim. With this construction, the wire bears hard against the outer corner 11 of the basket 90 rim, thereby preventing inward displacement of the portions B of the handle toward each other. It will be understood, of course, that steel wire is preferably employed for this purpose, or wire having a suitable 95 amount of stiffness and rigidity, and that when the fastening devices E are clamped on the basket rim, as shown in Figs. 1 and 3, the said rim is tightly gripped between the outer and inner portions of the said fastening devices. 100

From the foregoing it will be seen that handles made up in this manner can be readily applied to the baskets by the users thereof, as the baskets can be made with 105 holes to receive the prongs 1, or these holes can be made afterward and when needed.

Thus the wire crosses the upper edge of the basket rim and bears directly against the outer corner of the rim, at each side of 110

the basket, thereby preventing inward displacement of the side portions of the handle away from the basket rim. The fastening devices thus formed by bending the 5 end portions of the wire serve to readily clamp the handle in place on the basket rim. The inverted T-heads formed by the portions 4, 5, 6, 7, 8, 9 and 10 bear tightly against the rim, preferably at the outside, and prevent 10 tilting of the basket in the handle.

What I claim as my invention is:—

1. A basket provided with a wire handle having the ends of the wire inserted through the sides of the basket at points a distance 15 below the upper edges thereof, the wire then extending upwardly and over said edges, then downwardly against the basket, then upwardly against the basket, thereby forming depending jaws, and then extending 20 across the basket to form the grip of the handle, said basket having a thickened rim, and said handle being formed with sides held against inward displacement by portions of the wire which engage the outer 25 and upper edges of said rim, which portions communicate the pull of the handle directly to the outside of the basket, said jaws being elongated horizontally to form inverted T-heads for the handle which bear against the 30 outer sides of said rim.

2. A basket provided with a wire handle having the ends of the wire inserted through the sides of the basket at points a distance below the upper edges thereof, the wire then 35 extending upwardly and over said edges, then downwardly against the basket, then

upwardly against the basket, thereby forming depending jaws, and then extending across the basket to form the grip of the handle, said basket having a thickened rim, 40 and said handle being formed with sides held against inward displacement by portions of the wire which engage the outer and upper edges of said rim, which portions communicate the pull of the handle 45 directly to the outside of the basket, said jaws being elongated horizontally to form inverted T-heads for the handle which bear against said rim.

3. A basket provided with a wire handle 50 having the ends of the wire inserted through the sides of the basket at points a distance below the upper edges thereof, the wire then extending upwardly and over said edges, then downwardly against the basket, 55 then upwardly against the basket, thereby forming depending jaws, and then extending across the basket to form the grip of the handle, said basket having a thickened rim, and said handle being formed with 60 sides held against inward displacement by portions of the wire which engage the outer and upper edges of said rim, which portions communicate the pull of the handle directly to the outside of the basket, said jaws being 65 elongated horizontally immediately above said ends to form inverted T-heads for the handle which bear against the outer sides of said rim.

Signed by me at Chicago, Illinois, this 70
17th day of March, 1915.

EDWARD CRAIG.
